United States Patent Office

Des. 222,567

Patented Nov. 2, 1971

222,567

GARMENT DISPLAY FIXTURE

Maurice Cohen, 3580 NW. 52nd St.,
Miami, Fla. 33142

Filed Mar. 23, 1970, Ser. No. 22,004

Term of patent 14 years

Int. Cl. D6—01

U.S. Cl. D80—8

FIG. 1

FIG. 2

FIG. 3

FIG. 4

FIG. 1 is a perspective view showing a garment display fixture embodying my new design;

FIG. 2 is an elevational view thereof;

FIG. 3 is a top plan view thereof; and

FIG. 4 is a bottom plan view thereof.

I claim:

The ornamental design for a garment display fixture, substantially as shown.
